COMPRESSION TYPE REFRIGERATING SYSTEM

Walter A. Kuenzli and Charles B. Leeson, Evansville, Ind., assignors to Servel, Inc., New York, N. Y., a corporation of Delaware

Application October 31, 1932, Serial No. 640,379

7 Claims. (Cl. 62—115)

Our invention relates to refrigerating systems of the compression type and more particularly to such systems in which a receiver or liquid accumulator is connected in the system between the condenser and evaporator.

When, in such systems, a water cooled condenser has been employed together with a water control valve connected to be operative responsive to the pressure in the high pressure side of the system, it has been found that when the compressor is shut down the water control valve does not always operate to shut off flow of cooling water, which results in waste. In accordance with our invention this unsatisfactory operation is corrected preferably by connecting a check valve in the system between the condenser and the receiver.

A more complete understanding of our invention may be had from the following description taken in connection with the accompanying drawing, in which,

The figure shows diagrammatically a compression type refrigerating system provided with a check valve in accordance with our invention.

Referring to the drawing, there is shown diagrammatically a well known compression type refrigerating system comprising a compressor 10 driven by a motor 11, a condenser 12, receiver 13, and evaporator or expansion coil 14. The condenser 12 comprises an outer coil of tubing 15 and an inner concentric liquid circulating or cooling coil 16. Obviously, it is immaterial whether the cooling liquid, in most instances water, is circulated through the inner coil 16 or the outer coil 15, the refrigerant being circulated through the other coil.

In operation, the vapor of the refrigerant being utilized, which for purposes of description may be methyl chloride, is compressed in the compressor 10 and delivered through conduit 17 to the condenser 12 where it is condensed to liquid. The liquid refrigerant passes from the condenser 12 through conduit 18 into the receiver 13 from where it is delivered through conduit 19 and the control means 20 into the evaporator or expansion coil 14. The control means 20 is any kind of manually or automatically controlled or even fixed pressure reducing or liquid flow regulating device and for purposes of description may be an expansion valve. Due to the reduction in pressure on passing through the control valve 20 into coil 14 the liquid refrigerant evaporates, the heat of vaporization being supplied by the surrounding medium thus producing a refrigerating effect.

The refrigerant vapor is returned to the compressor 10 through conduit 21.

The flow of water through the coil 16 is indicated by the arrows in the drawing and is controlled by a valve 22 responsive to the pressure in the system on the high pressure side of the compressor. The automatic water control is shown diagrammatically to represent a pressure responsive device in which the valve 22 is operated by a bellows 23 connected to the high pressure side of the refrigerating system through conduit 24. The valve 22 is designed to open and allow the flow of water when the pressure in the condenser reaches a predetermined value and to close when the pressure drops below this value.

It is, of course, well known that this type of refrigerating system in household service is not operated continuously but that its operation is intermittent, that is, divided into alternate operating and idle periods of lengths depending upon the refrigeration demand. It has been found that when the compressor stops at the end of an operating period the control valve 22 does not always close to terminate the flow of cooling water through the condenser. It has been found that this occurs when the receiver 13 is subjected to a temperature above that of the condenser, the latter being determined of course by the temperature of the cooling water supply.

When the compressor is shut off no more high pressure gas is delivered to the condenser and the flow of cooling water causes condensation of gas in the condenser which should cause a drop in pressure and closing of the water supply valve 22 in response thereto. However, when the cooling water temperature is below that of the air around the receiver 13, liquid refrigerant in the latter evaporates, and the vapor flowing back through conduit 18 exerts pressure on the liquid in the condenser so that the condenser pressure will not drop below that at which the control valve 22 is set to close and thus cooling water continues to flow during the idle periods, which results in waste of water.

In order to overcome this difficulty we locate a check valve 25 in the conduit 18 between the condenser and receiver. This check valve may be of any known structure which allows flow of fluid through conduit 18 in only one direction, from the condenser toward the receiver. By the use of this check valve, when the compressor stops at the end of an operating period, and, as described above, liquid refrigerant begins to evaporate in the receiver 13, the check valve prevents flow of vapor from the receiver toward the con-

denser wherefore the pressure in the condenser drops, due to condensation therein, without further supply of vapor, and continues to drop past that pressure at which the water control valve 5 22 is set to operate and the flow of cooling water is shut off during the idle period.

It will be obvious to those skilled in the art that various changes may be made in the construction and arrangement without departing from 10 the spirit of the invention and therefore the invention is not limited to what is shown in the drawing and described in the specification but only as indicated in the following claims.

We claim:

- 15 1. In a refrigerating system of the compressor-condenser-expander type, a condenser comprising a pair of concentric tubes, means for circulating cooling liquid through one of said tubes, means for controlling circulation of liquid through said 20 tube responsive to the pressure in the condenser, a closed receptacle connected to receive condensate from said condenser, and automatic means for allowing fluid flow only from said condenser toward said receptacle.
- 25 2. In a refrigerating system of the compression type, a tubular type condenser, means for cooling said condenser, means for controlling the operation of said cooling means responsive to the pressure in the high pressure side of the system, 30 an accumulating chamber connected to receive liquid from said condenser, and automatic means for preventing fluid flow from said chamber toward said condenser.
- 35 3. In a refrigerating system of the compressor-condenser-expander type, a condenser comprising a pair of concentric tubes, means for circulating cooling liquid through one of said tubes, a valve for controlling circulation of liquid through said 40 tube operative responsive to the pressure in the condenser, a liquid receiver connected between said condenser and the expander, and a check

valve for automatically preventing flow of fluid from said receiver toward said condenser.

4. In a refrigeration system of the compression type, a compressor, a condenser, means for cooling said condenser operable responsive to pressure in the high pressure side of the system, an accumulating chamber connected for unrestricted flow of condensate from said condenser thereto, and means for preventing return flow of fluid from said chamber toward said condenser when said compressor is idle.

5. In a refrigeration system of the compression type, a condenser, means for cooling said condenser, means for controlling the operation of said cooling means responsive to pressure in the high pressure side of the system, an accumulating chamber connected for unrestricted flow of condensate from said condenser thereto, and automatic means for preventing return flow of fluid from said chamber to said condenser.

6. In a refrigeration system of the compression type, a water cooled condenser, a valve for controlling the flow of cooling water responsive to the pressure in the condenser, a receiver connected for unrestricted flow of condensate from said condenser thereto, and a check valve for automatically preventing return flow of fluid from said receiver to said condenser.

7. In a refrigeration system of the compressor-condenser-expander type, a condenser comprising a pair of concentric tubes, means for flowing cooling water through one of said tubes, a valve for controlling flow of water through said tube responsive to pressure in the condenser, a receiver connected for unrestricted flow of condensate from said condenser thereto, and automatic means for preventing return flow of fluid from said receiver to said condenser.
